CLOSURE FOR CANS

Letcher O. Grice, United States Army,
Washington, D. C.

Application March 17, 1942, Serial No. 435,031

2 Claims. (Cl. 222—481)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to portable liquid containers and more particularly to a novel and improved container closure device particularly adapted for use in connection with a sheet metal can intended for supplying drinking water to soldiers during maneuvers or combat.

It will be apparent to those skilled in the art that a closure of this type and intended for this use must have certain characteristics whereby it is especially adapted for its purpose in that it must be capable of completely and positively sealing the can against egress of liquids and must be arranged to open readily and present a sufficiently large filling orifice so that the can may be filled from almost any source, or so that the interior of the container may be cleaned, and, at the same time, it is essential that the container closure be so designed that small amounts of liquid may be dispensed into small-necked receptacles, such as canteens, without any waste of the water by spilling.

Further, in any type of structure intended for use by troops in active service in the field, it is absolutely essential that the structure be of such mechanical design as to be extremely rugged and capable of withstanding great physical abuse without damage. It will also be readily apparent that it is highly desirable to provide means for closing the dispensing opening of the liquid container to prevent accumulation of dirt or foreign substances in the dispensing spout when the containers are being transported from one location to another.

It is, therefore, the prime object of the present invention to provide a portable liquid container including a relatively large cam-locked closure cap adapted to be opened for filling or cleaning of the container and arranged to carry a small dispensing valve or spigot to provide satisfactory means of accurately controlling the flow of the liquid during dispensing and to facilitate the filling of canteens or other containers having small necks.

A further object of the invention is to provide a relatively large cam-locked container cap having a deep recess in the cap and a small dispensing valve in the recess so that the valve structure is substantially below the rim of the cap and is thus protected against accidental damage that might be caused from impact of

any exterior forces against the closure mechanism of the can.

A further object of the invention is to provide a portable water container including a relatively large cam-locked filling cap arranged to assume a normal position at an acute angle with respect to the horizontal when the can is standing in normal position and having a deep recess including a vertical wall at one side and a bottom comprising a plane marginal surface and a frusto-conical cavity, with a dispensing valve mounted at the lower portion of the cavity, and so arranged that it may be rotated on its axis; the valve being provided with a dispensing spout extending angularly upwardly and arranged so that it may be directed toward the lower side of the closure cap to project above the margin of the cap and extend outwardly from the plane of the cap to facilitate the discharge of the fluid, or so that it may be rotated one-half revolution to a point where the end of the dispensing spout substantially abuts the vertical side wall of the cavity to substantially close the dispensing spout and to retain a telescoping sleeve in position on the spout; thus preventing entry of dirt or foreign substances into the dispensing valve.

A further object of the invention is to provide a portable liquid container closure including a knockout plug arranged to provide an optional mounting for a dispensing valve, the arrangement being such that the knockout plug is located at the lowermost point in a deep cavity in the closure cap and is thus entirely surrounded by the rim of the cap at a point substantially above and spaced away from the removable portion of the knockout plug so that it is not easily subject to accidental damage by contact with foreign obstacles when in use.

These and other important objects are accomplished by the peculiar construction and arrangement of parts of the present preferred embodiment of the invention as illustrated in the drawings attached hereto and forming a part of this specification in which:

Fig. 1 is a side elevational view of a standard form of Army water container equipped with the container closure forming the subject matter of the present application.

Fig. 2 is an enlarged detail sectional view of the container closure.

Fig. 3 is a detail sectional view of the container vent.

Fig. 4 is an enlarged plan view of the container closure provided with a dispensing valve,

Fig. 5 is a detail sectional view of the container closure provided with a dispensing valve,

Fig. 6 is a rear elevational view of the container closure illustrated in Figs. 4 and 5,

Fig. 7 is a detail perspective view of the closure cap in closed position with the dispensing valve in operating position, and

Fig. 8 is a perspective view of the closure in open position.

In the illustrations of the present application, the improved form of container closure is shown as attached to a standard Army gasoline container which is of generally rectangular shape including relatively flat sides 11 joined to the narrow end portions 13 and 14.

As shown in the drawings, the top 16 of the container is made of a single piece of sheet metal formed into the desired shape and united to the body of the can by rolled or welded bead 18 extending completely around the can. The top portion 16 of the can is drawn from a single piece of sheet metal, as pointed out above, and is shaped to include a hump 21 at one end, adjacent the end wall 14, and an inclined portion 23 at the other end. The inclined portion 23 is positioned at an acute angle with respect to a horizontal plane, and is at a level substantially below the top of the hump 21. The center portion of the can is formed as a relatively horizontal portion 24 extending from the lower edge of the hump to the upper edge of the inclined portion 23.

The container is also provided with a triple handle structure which, in the present drawings is shown as being formed of a single piece of sheet metal, rolled to provide three separate handles extending from a point adjacent the upper end of the inclined portion 23 to the top of the hump 21. This handle structure includes a web 27 having a flange 25 adapted to lie flat against the upper end of the inclined portion 23 and welded onto the portion 23 in order to secure the forward end of the handle.

The forward web 27 is trifurcated at its upper end to provide three separate horizontal handle portions 28, 29 and 30, each of which is rolled from the sheet metal of which the structure is constructed so that they each are substantially cylindrical in cross-section.

It will be noted from Figs. 3, 5, 7 and 8 that the handles are united to each other by the web 27 which is cut away along a gradual curve extending well below the plan of the top of the handles.

The container is also provided with a vent screw 31 threaded into the threaded flange 32 at a point on the hump 21. A vent port 33 extends up through the center of the screw to the side port 34, so that when the screw is tightened the gasket 35 will close the vent, but when the screw is loosened, the port 34 will be exposed to provide an unobstructed air inlet when liquid is being poured from the mouth of the container. The lower end of the screw 31 is split at 36 to retain it against removal.

The inclined surface 23 of the can top 16 is provided with an upwardly extending neck 37 drawn from the metal of the can top. This neck portion 37 fits into a sleeve 38 and is securely fastened to it by welding or other means. The sleeve 38 extends upwardly a short distance above the inclined portion 23 of the can and is rolled around a metal reinforcing ring 39 to provide a reinforcing rim including an upper flange surface 52 adapted to be sealed by the closure cap 61.

The reinforcing ring 39 is also provided with a pair of cam anchor ears 58 and 59, one at each side of the mouth of the container, which will cooperate with the cam mechanisms of the cap to be hereinafter described.

The closure cap 61 of the container comprises a sheet metal structure of generally circular shape having an annular flange 62 and a hinge extension 63 extending to a hinge pin 55 carried on a hinge bracket 53, which is formed of sheet metal and is welded or otherwise secured to the exterior surface of the sleeve 38 adjacent the mouth of the container.

From an examination of Fig. 2, it will be apparent that the lower surface of the cap structure 61 will move into approximate sealing engagement with the upper surface 52 of the reinforcing rim around on the container mouth. To provide a dependable leak-proof sealing mechanism an annular gasket 67 is mounted on the lower face of the cap in a metal gasket ring 68 including inner and outer flanges to prevent the gasket from spreading.

The cap is clamped against the cup by novel cam operated structure including a particular configuration of cams so designed that the cam surfaces are well protected against accidental damage and including a cam operating plate of novel design and construction whereby it is well adapted to exert comparatively large forces against the cams to effect tight sealing of the container and equally adapted to be easily clamped and released without the use of tools.

A cam operating plate 71 is mounted on rivets 72 and 73 secured to the top of the cap 61 and the plate is formed of a relatively flat central section 75 and two downwardly extending side webs 76 and 77, one positioned on either side of the cap 61. This structure gives great rigidity to the cam locking plate since the opposite side corners 78 and 79 of the folded metal sheet reinforce the side webs and give relatively greater strength to the plate, so that it is adapted to resist heavy impacts from external sources without damage either to the cam locking plate or to the closure structure; all essential parts of which are protected by the plate. The locking means themselves comprise internal cam flanges 81 and 82 each extending inwardly from the lower surface of the webs 76 and 77, respectively, and positioned to ride under the cam anchors 58 and 59 respectively, and to exert a cam action to draw the rivets 72 and 73 downwardly, and force the cap 61 into firm sealing engagement with the flange 52 of the sleeve 38. Thus, to seal the container, it is only necessary to pivot the cap 61 downwardly above the pivot pin 55, engage the cams 81 and 82 under the cam anchors 58 and 59 respectively, and force the cam plate downwardly against the container cap to the position shown in Figs. 1, 2, 4, 5, 6 and 7.

It may be well to point out that the container may be opened or closed entirely without the use of tools. Further, it is possible to exert a great degree of force on the cam surfaces, since the rearward end of the cam locking plate 71 includes the relatively flat, broad smooth surface 75 on which the operator may exert a considerable force without injuring his hands.

The cam locking plate 71 is bifurcated at its extreme end to provide a pair of ears 84 and 85, and each of these ears is arranged to assume a position between two of the adjoining handle portions of the container and slightly below the upper horizontal surface of the handles (see Figs.

3 and 5). These ear portions are particularly useful in releasing the cams and opening the container closure since they project well beyond the upper end of the forward web 27 of the handles so that there is unobstructed clearance below the ears 84 and 85 and between the handle portions 28, 29 and 30. To open the container, the operator may reach between the handles and firmly grip either or both of the ears 84 and 85 to lift the locking plate 71. This arrangement also makes it possible to obtain a good mechanical advantage since the ears are at the extreme ends of the locking plate, and it will therefore be obvious that a relatively large amount of force may be exerted by use of the bare hands and that no types of tools will be required to release the cams and open the container cap.

The entire cap structure lies at a substantial angle with respect to the horizontal when the can is in normal position, and a cavity is formed in the upper surface of the cap by drawing the sheet metal downwardly to provide a substantially horizontal margin 91, intersecting the plane of the top of the cap at its lower side and bounded by a substantially vertical side wall 92 at the opposite side of the cap. This cavity facilitates the mounting of a dispensing valve and pouring spout on the closure cap.

For the purpose of mounting the valve it is desirable to provide a knockout plug so that the containers need not necessarily be equipped with the valve at the time of manufacture but may be shipped to the field with the ordinary form of can closures, and, when necessary, the individual containers may be separately equipped with dispensing valves and spouts that are separately manufactured and issued to the troops as a separate item of issue. It has been discovered, however, that the provision of a satisfactory structure of this character is not as simple as it may at first appear since the only convenient method of attaching a dispensing valve is by the use of a knockout plug in the container or closure, but the use of any such knockout plug is unsatisfactory unless the device is so arranged that the plug is not apt to be struck by foreign substances during the rough handling that any container of this character will necessarily receive in field service. Obviously, if a knockout plug is positioned at any unprotected point on the surface of the container or closure, it is quite apt to be struck by the corner of some other container when they are being stacked or handled, and, of course, if the plug is knocked out, the container will be completely unsatisfactory for use until some repair is made.

The disadvantage of the use of knockout plugs has been overcome in the present invention by positioning the plug at the bottom of the cavity in the closure cap where it is located at a point well below the rim of the cap and thus well protected against being struck by any exterior force; in fact, as illustrated in the drawings, the recess of the closure cap is provided with a downwardly extending frusto-conical cavity 93 terminating on a flat base portion 94 in which the knockout plug 95 is located.

This frusto-conical cavity not only provides additional protection for the knockout plug, but also serves another valuable purpose in that it permits a novel and highly advantageous type of mounting for a liquid dispensing valve and pouring spout. To install the valve and spout, it is only necessary to knock out the plug 95 and insert the threaded shank 101 of the dispensing valve 102 through the opening and to resiliently

lock the valve structure in position by threading the retaining nut 103 onto the external threads of the shank 101 to compress the spring washer 104, against the lower surface of the closure cap 5 and thus apply sealing pressure to the gasket 105 on the upper surface. It will be understood, of course, that the retaining nut 103 can be adjusted to proper position to provide sufficient friction so that the valve structure can be rotated but will be frictionally held in any position and the nut may be prevented from unscrewing by marking the threads of the valve with a center punch or by any other convenient method.

The valve shank 101 is provided with a tapered 15 valve seat at its lower extremity which is normally maintained closed by a valve 106. The stem of the valve 106 extends upwardly through the packing 107 in the valve body and is secured to the valve button 108 at the top of the valve body. A coiled wire spring 109 is also provided around the valve stem to lift the valve and maintain it in closed position.

The pouring spout 110 of the valve projects outwardly and upwardly at an incline corresponding to the angular inclination of the frusto-conical walls of the recess 93 and is arranged to be shifted from the full line inoperative position shown in Fig. 5 to the dispensing position illustrated in Fig. 7. It will be obvious that when 30 the valve spout is in the dispensing position, the liquid container may be inverted, the vent opened, and the liquid may be dispensed accurately and in small quantities from the spout 110 of the valve.

When the container is not being used for immediate dispensing, the spout 110 is covered by 35 a telescoping sleeve 111 and the valve rotated by means of the thumb wings 112 to the full line position illustrated in Fig. 5. At this time the end of the spout 110 will be substantially in abutment 40 with the vertical side wall 92 of the recess 93 of the closure cap, and the side wall will prevent the sleeve 111 from being removed, thus preventing any possibility of dirt or foreign substances reaching the valve spout. The cap is secured to 45 one of the valve wings 112 by a small flexible retaining chain 113 to prevent the cap from being lost when the container is in use.

From the foregoing description, it is believed 50 apparent that the present closure structure provides a simple mechanism of great utility and unquestionable value in that it accomplishes all of the above mentioned objects of the present invention by the use of a very simple mechanical structure adapted to mass production methods 55 of manufacture, easy to install, and at the same time of such mechanical designs as to be well adapted to resist rough handling and a high degree of abuse that structures of this character must necessarily withstand in the field in use by 60 troops in active combat.

The present invention has been developed in 65 the United States Army and adopted by the Army as the most successful device of its character yet devised, but while it is particularly adapted to military use and has been designed essentially for military purposes, it is believed to have utility in commercial fields as well, and it is therefore requested that the scope of the invention be limited only by the limitations of the appended claims.

Having thus described my invention, I claim:

1. In combination, a container having a depressed area in a portion of its top forming a recess for housing and protecting a pouring spout, said recess having a flat bottom extending inwardly at one side from the plane of the adjacent

top surface and joined to the top by a wall of gradually increasing height through the rest of its periphery, the center of the bottom being counter-sunk and provided with an aperture, and a tubular valved spout rotatably mounted in said aperture, the spout having a threaded portion projecting through the aperture and secured therein and an angular extension which projects above the top when turned into pouring position at the shallow side of the recess and which abuts the wall when turned toward the deep side of the recess, said threaded portion having a passage therethrough and a valve seat at its lower end, and a reciprocating valve adapted to engage said seat and having a stem extending upwardly through the wall of said spout adjacent the angular extension to form an operating member.

2. In combination, a portable liquid container including a relatively large outlet having an up-standing rim and a cap for closing said outlet pivotally mounted on said rim, said cap having a

recess formed by a counter-sunk top portion, the bottom of said recess lying at an angle to the top of the cap and being merged with the top at one side and joined thereto by a wall of increasing depth around the remainder of its periphery, said bottom having a central aperture, and a spout comprising a tubular element having a vertical section and an angular section, said vertical section having a valve seat at its lower end and a reciprocating valve mounted therein and biased to close the lower end, said valve having a vertically extending stem projecting from said tubular element adjacent the angular section and forming an operating member, said vertical section being rotatably mounted in said aperture, whereby said angular section projects beyond the top of the cap when it is turned toward the shallow side of the recess but lies within the recess when turned toward the deep side.

LEITCHER O. GRICE.
